US00D768723S

(12) **United States Design Patent** (10) Patent No.: **US D768,723 S**
 Anzures et al. (45) Date of Patent: ** Oct. 11, 2016

(54) **DISPLAY SCREEN OR PORTION THEREOF WITH A SET OF GRAPHICAL USER INTERFACES**

(71) Applicant: **Apple Inc.**, Cupertino, CA (US)

(72) Inventors: **Freddy Anzures**, San Francisco, CA (US); **Imran Chaudhri**, San Francisco, CA (US); **Alan C. Dye**, San Francisco, CA (US); **Jonathan P. Ive**, San Francisco, CA (US); **Wan Si Wan**, Sunnyvale, CA (US); **Christopher Wilson**, San Francisco, CA (US); **Lawrence Yang**, San Francisco, CA (US)

(73) Assignee: **Apple Inc.**, Cupertino, CA (US)

(**) Term: **15 Years**

(21) Appl. No.: **29/540,717**

(22) Filed: **Sep. 27, 2015**

Related U.S. Application Data

(63) Continuation of application No. 29/519,766, filed on Mar. 6, 2015.

(51) **LOC (10) Cl.** **14-04**

(52) **U.S. Cl.**

USPC **D14/495**

(57) **CLAIM**

The ornamental design for a display screen or portion thereof with a set of graphical user interfaces, as shown and described.

DESCRIPTION

The FIGURE is a front view of a display screen or portion thereof with a set of graphical user interfaces showing our new design.

The broken lines in the FIGURE show a display screen or portion thereof, and form no part of the claimed design.

1 Claim, 1 Drawing Sheet
